ISOMERIZATION AND ALKYLATION OF NORMAL PARAFFINS

Louis A. Clarke, Fishkill, N. Y., assignor to The
Texas Company, New York, N. Y., a corporation
of Delaware

No Drawing. Application April 10, 1942,
Serial No. 438,418

10 Claims. (Cl. 260—683.4)

1

This invention relates to the manufacture of motor fuel hydrocarbons of good anti-knock and other desirable properties and to the production of isobutane from normal paraffin and olefin hydrocarbons. More particularly, the invention relates to a process for alkylating a normal paraffin hydrocarbon with an olefin and concomitantly isomerizing the normal paraffin hydrocarbon, utilizing a mixed catalyst containing as essential constituents substantially anhydrous liquid hydrofluoric acid and boron fluoride.

A number of catalysts have heretofore been proposed for alkylating an isoparaffin, such as isobutane, with an olefin to produce motor fuel hydrocarbons or alkylate of a substantially saturated isoparaffinic character having high anti-knock value, such as sulfuric acid, HF, $\text{BF}_3 \cdot \text{H}_2\text{O}$ complex, and the like. None of the above catalysts have been found effective for alkylating a normal paraffin with an olefin, and any normal paraffin present in the hydrocarbon charge remains as a diluent which does not take part in the reaction. U. S. Patent No. 2,217,019 has proposed the use of a catalyst consisting of boron fluoride, nickel, HF and/or water, wherein the HF is in a minor proportion by weight with respect to the BF_3 , as a catalyst for promoting the usual alkylation reaction of isobutane with a normally gaseous olefin. This is also described in Journal of the American Chemical Society, volume 57-2, September 1935, pages 1616-1621, wherein it is stated that a normal paraffin does not take part in the reaction.

It has now been discovered that, by the use of a different and critical proportion range of substantially anhydrous liquid HF to BF_3 wherein the HF is maintained in excess of the weight of the BF_3 , a normal paraffin can be alkylated with an olefin to produce good yields of normally liquid substantially saturated hydrocarbons within the gasoline boiling range having good volatility and boiling point distribution characteristics and other desirable properties including relatively high octane. At the same time, this catalyst functions as an isomerization catalyst in the presence of the alkylation reaction and a good yield of isobutane, which can be employed for the conventional isoparaffin alkylation operation, is obtained. This is all the more remarkable since the combined catalyst of the present invention is inactive at the temperatures employed herein to effect isomerization of normal paraffins in the absence of a small but effective amount of olefin and the concomitant alkylation reaction; and the constituents of the catalyst employed separately are ineffective at the temperatures employed herein for producing alkylation of a normal paraffin with an olefin.

An object of the present invention resides in producing good yields of motor fuel hydrocarbons and of isobutane from normal paraffin and ole-

2

fin hydrocarbons, particularly the normally gaseous hydrocarbons of the character of normal butane, ethylene and propylene, which are available in large quantities as refinery waste gases and have not found extensive utilization in alkylation, polymerization or other processes for the production of more valuable normally liquid hydrocarbons of the character of motor fuel and aviation gasoline.

Another object of the present invention is to produce from such normal paraffin and olefin hydrocarbons a high-grade blending stock for motor fuel or aviation gasoline, and also substantial quantities of isobutane which can be employed in conventional alkylation processes for the production of increased quantities of high-grade alkylate. Other objects and advantages of the present invention will be apparent from the following description and the appended claims.

In accordance with the present invention, a normal paraffin hydrocarbon is reacted with an olefin under alkylation and isomerizing conditions in the presence of a mixed catalyst consisting essentially of a major proportion by weight of substantially anhydrous liquid HF and a minor but effective proportion by weight of BF_3 .

The catalyst may be prepared by introducing a stream of BF_3 into a body of anhydrous liquid HF maintained under pressure until the desired quantity of BF_3 has been added. It has been determined that a proportion of BF_3 by weight which is less than the weight of the HF is critical in effecting the alkylation and isomerization reactions of normal paraffins of the present invention. On the other hand, the presence of more than two mol percent of BF_3 is essential, and a proportion range of about four mol percent to twenty mol percent of BF_3 , equivalent to about 14-85% by weight based on the weight of the HF, or 12-46% by weight based on the weight of the mixed catalyst, is generally employed.

Anhydrous HF is a colorless, limpid liquid having a boiling point of 19.4° C. (66.9° F.), a melting point of -83° C. and a density of 0.9918 at 4° C. BF_3 is a fuming gas having a boiling point at atmospheric pressure of -101° C., a melting point of -127° C. and a density of 2.34 as compared to air which equals one. The temperature and pressure conditions of the present reaction are ordinarily such that the HF is maintained liquid, while the BF_3 is a gas. However, a substantial quantity of BF_3 passes into solution in the HF and the hydrocarbon charge of the reaction zone, so that the mixed catalyst comprises anhydrous liquid HF containing dissolved BF_3 and usually with a superimposed atmosphere of gaseous BF_3 , particularly in the higher portion of the BF_3 proportion range.

While it is possible that a compound is formed by reaction of HF with BF_3 , any compound thus formed is highly unstable since the components

of the catalyst may be separately recovered upon release of pressure without substantial loss. While the preferred catalyst is substantially anhydrous, a small amount of water may be introduced with the hydrocarbon charge and picked up by the catalyst without impairing its efficiency, so long as the water content does not approach an amount which will react with the BF_3 to form complex and thereby reduce the available or free BF_3 below the critical range specified above. For purposes of the present description and claims, it is to be understood that a catalyst containing this very small amount of water is included in the expression "substantially anhydrous." The catalyst of the present invention is thus distinguished from that which is prepared by adding BF_3 to an aqueous solution of HF or which contains an appreciable amount of water forming complex with the available BF_3 .

Both normally gaseous and normally liquid paraffin hydrocarbons of straight chain structure, such as normal butane, normal pentane, normal hexanes and other higher boiling paraffin hydrocarbons within the gasoline boiling range and up to about C_{12} paraffins, can be employed as the normal paraffin constituent of the charge. Likewise, various mixtures of these hydrocarbons, as well as mixtures of normal paraffin and isoparaffins are suitable. Normal butane is preferred since large quantities are available which are not normally required for blending purposes in motor fuels to impart volatility. A paraffinic naphtha, such as a straight run naphtha, can likewise be utilized with substantial improvement in the volatility and other characteristics of the treated product. Likewise, both normally gaseous and normally liquid olefins are suitable. The normally gaseous olefins, namely, ethylene, propylene and the butylenes, are preferred; but low boiling normally liquid mono-olefins and the low boiling olefin polymers, such as selective polymers of the character of di-isobutylene and tri-isobutylene, cross-polymers between isobutylene and normal butylenes, non-selective C_3 — C_4 olefin polymers, and the like, can be employed.

The normal paraffin is utilized in at least an equal molar ratio with respect to the olefin, and preferably in a substantial molar excess thereof. For example, molar ratios of normal paraffin to olefin of 1:1 to 50:1 and higher are contemplated; and generally a molar ratio in excess of 5:1 and preferably about 10:1 is used. By recycling emulsion or a portion of the hydrocarbon phase of the reaction products in accordance with conventional isoparaffin-olefin alkylation practice, an even higher ratio at the point of contact of the hydrocarbon feed with the catalyst may be maintained.

Ordinarily, mild temperatures within the range of 0 to 150° F. and above are contemplated, with temperatures of about 70–130° F. being generally preferred. The temperature employed varies with the hydrocarbon charge stocks and the ultimate or main purpose of the reaction. For example, in the alkylation of a normal paraffin with C_3 and C_4 or higher olefins, a temperature of about 50–90° F. is quite suitable. In the alkylation of a normal paraffin with ethylene, a temperature range of about 70–140° F. is usually employed, and good results have been obtained at as low a temperature as about 70° F. Where isomerization of normal paraffin in the presence of a relatively small amount of olefin constitutes the main reaction, temperatures in the upper

portion of the range, for example, 70–150° F., are quite satisfactory. Sufficient pressure is utilized to preferably maintain at least the normal paraffin constituent of the hydrocarbon charge as well as the HF in liquid phase, and to keep the desired quantity of BF_3 in the reaction zone. The superimposed vapor pressure of the BF_3 may determine the pressure maintained in the reaction zone which will usually be about 100–250 pounds per square inch, although this can be varied and both higher and lower pressures employed.

A ratio of catalyst to total hydrocarbons maintained in the reaction zone of about 0.1:1 up to 2:1 by liquid volume may be employed, with a ratio of about 1:1 by liquid volume usually preferred. A contact time of about 20–120 minutes may be used with about 60–90 minutes generally preferred. The reaction is preferably carried out with efficient agitation, as by high-speed mechanical stirrer, circulating pump or mixer, and the like, to provide intimate contact between the hydrocarbons undergoing reaction and the catalyst.

The reaction may be carried out either in batch or continuously. In a typical batch procedure, a steel reaction bomb equipped with a mechanically-driven stirrer has been employed. The reactor was charged with the required amount of anhydrous liquid HF and the liquefied normal paraffin. BF_3 was then introduced as a gas and the stirring mechanism started. The olefin was then charged at a regular rate over the required time interval, usually about sixty minutes, and then the stirring was continued an additional thirty minutes. The contents of the reactor were passed through a caustic scrubber to remove the HF, and then into a stabilizer where the bulk of the gases were fractionated off and collected. The stabilized alkylate was fractionated to note the hydrocarbon boiling range distribution, and generally a 311° F. end point fraction of debutanized alkylate was collected and tested to obtain octane and other pertinent data. The offgases were generally analyzed by low temperature fractional distillation.

The following are results of typical batch runs carried out in the above described manner with normal butane as the paraffin constituent of the charge and with ethylene, propylene and isobutylene as the olefin constituent:

1 n-Butane. 2 Ethylene. 3 Propylene. 4 Isobutylene.

The stabilized alkylate obtained in each of the above runs consisted largely of pentanes and hexanes with considerable isopentane. The results show that alkylation is accompanied by fragmentation reactions, resulting in the formation of large percentages of isopentane and hexanes regardless of the olefin charged. At least about 95% of the stabilized total alkylate boiled below 300° F. in all instances, this product having a bromine number of less than 1 showing substantial saturation. As representative of the character and boiling point distribution of the alkylate produced, the following is an analysis of the alkylate obtained in run No. 4:

Pentanes, 37% by volume of which 25% on the 15 volume of the total alkylate was isopentane
Hexanes, 27%
Heptanes, 13%
Octanes, 13%
Above octanes, 10%

In all of the runs, with the exception of No. 3, it will be noted that the offgas contained more than 40% by weight of isobutane; and in run 25 No. 1, with ethylene as the olefin constituent, the isobutane content of the offgas was 66.5% equivalent to 171% on the basis of the olefin charged. Run No. 3 indicates that the temperature of 30° F. employed was too low for the isomerization reaction to secure high yields of isobutane, although a fair yield of alkylate resulted. Runs Nos. 3, 4 and 5 give a comparison of operations with normal butane and isobutylene at temperatures of 30° F., 74° F. and 115° F. respectively, and show improved results at the higher temperatures.

The following series of batch runs indicate the effect of the ratio of HF to BF₃ in the mixed catalyst. These runs were all carried out in the batch reactor described above with a normal butane to isobutylene molar ratio of 5:1 and a reactor temperature of 70-75° F.:

Table II

	Mols HF	Mols BF ₃	Mol percent BF ₃	Yield Alkylate Wt. percent on Olefin	Percent Isobutane in Offgas	Yield Isobutane Wt. percent on Olefin
1	10.5	0	0	47 (polymer)	0	0
2	10.0	0.22	2	61	0	0
3	9.5	0.38	4	151	31.3	119
4	10.8	0.73	6	177	42.6	180
5	6.5	1.10	14	166	61.3	207
6	4.8	1.10	19	132	58.6	246
7	2.5	1.10	30	100	25.1	112

Run No. 1 shows that HF alone does not promote the alkylation of normal butane with isobutylene. Runs Nos. 2 and 3 show that the minimum effective concentration of BF₃ lies between about two mol percent and four mol percent, beneath which neither alkylation to any appreciable extent nor isomerization takes place. The above runs show that the best yield of liquid alkylate was secured with about 4-14 mol percent concentration of BF₃ in the catalyst, while the maximum yield of isobutane was obtained with about 6-19 mol percent concentration of BF₃. There was a sharp decline in both the alkylation and isomerization reactions between a BF₃ concentration of 19 and 30 mol percent.

Where isomerization or the production of isobutane is the primary purpose of the reaction, only a small proportion of olefin on the basis of the normal paraffin charge is used with the HF-BF₃ catalyst. The following series of runs 75

were made employing normal butane and the olefin polymer di-isobutylene with HF-BF₃ in mol ratio of 13:1:

Table III

N-butane/olefin ratio (mol)	HF-BF ₃ mol ratio 13:1			
	Olefin used di-isobutylene	10.4	14.1	20.8
Temperature, °F.		115	120	125
Yield stabilized alkylate, weight percent on olefin		252	238	220
Yield isobutane, weight percent on olefin		515	710	720
Yield isobutane, weight percent on n-butane		49.5	50.5	34.8
Weight discount isobutane in offgas		57.3	57.0	45.2

The above runs indicate that the highest conversion of normal butane to isobutane is secured with a molar ratio of normal butane to olefin of about 10:1 to 20:1, although substantial yields of isobutane are secured at ratios as high as 43:1. 20 However, it has been found that the HF-BF₃ catalyst is not effective in isomerizing or producing isobutane from either normal butane or normal pentane in the absence of olefin. About 1-2% of olefin based on the normal paraffin charge appears to be about the minimum which will produce effective reaction. This is contrary to previous practice in the isomerization art, where freedom from olefin in the normal paraffin charge was considered a desideratum to avoid catalyst deterioration and provide other advantages. Moreover, it will be noted that the isomerization or production of isobutane occurs in highly effective amount at comparatively low temperatures of the order of about 70-150° F. 30 under the conditions specified with the HF-BF₃ catalyst, whereas prior practices in the isomerization art generally utilized temperatures of the order of 200° F. and above to secure effective conversion.

As illustrating the effectiveness of the catalyst of this invention on other normal paraffins, the following three runs on normal pentane, normal heptane and a North Texas straight-run naphtha are listed:

Table IV

2 n-Heptane.

3 North Texas SR Naphtha Boiling range 96°-348° F., Original CFRM octane 63.2.

4 Isobutylene.

In each of these runs, it will be noted that the offgas consisted of more than 70% by weight of isobutane, and ran as high as about 90% in the run on normal heptane. In the normal pentane run, the alkylate contained a large percentage of isopentane, the balance being mainly hexanes, heptanes and octanes, with the major proportion boiling below the octane range and providing a similar high volatility for blending stock as obtained in the normal butane runs. In the case of normal heptane, the major proportion was converted to both lower and higher boiling hy-

drocarbons with a resultant C. F. R. M. octane increase from 0 to 72 for the converted alkylate, and a substantial proportion again boiling in the lower range providing high volatility. In the case of the straight run naphtha, the boiling range distribution of the alkylate was advantageously lowered with the concomitant production of a substantial amount of isobutane.

A series of continuous runs was also made in a rotary copper-lined reactor fitted with a steel shaft and impeller driven by an electric motor at about 1750 R. P. M. In starting up a continuous run, the required amount of anhydrous liquid HF was charged to the reactor, and then the system was filled with normal paraffin, such as normal butane, and gaseous BF_3 then added until the pressure in the system reached about 200 pounds per square inch. Then a mixture of the normal paraffin and olefin was added continuously while the contents of the reactor were agitated. The reacted mix overflowed at a corresponding rate to a long inclined settler where most of the HF and probably some of the BF_3 separated from the hydrocarbon phase and was continuously recycled to the reactor. The hydrocarbon phase containing some dissolved HF and a substantial amount of the BF_3 passed through a control valve to a caustic scrubber, and thence to the product receivers and stabilizers, where the offgases and BF_3 were removed from the stabilized alkylate. This alkylate was then distilled to separate into the desired fractions, such as a 311° F. end point fraction and any higher boiling residue.

In an alternative procedure, BF_3 was added continuously with the hydrocarbon charge to provide a portion of the required amount of BF_3 in the reaction zone and to make up for that which was removed with the reacted mix. In other runs, the paraffin charge was saturated with both HF and BF_3 at room temperature and about 150 pounds per square inch. In either case, the hydrocarbon charge was divided into two parts, one part being a mixture of normal butane with the olefin in the desired molar ratio of about 5:1 to 10:1, and the second part being the normal paraffin or normal butane saturated with HF and/or BF_3 . These two streams were charged continuously into the reactor which had been previously filled with catalyst and normal paraffin as described above, so that both HF and BF_3 were continuously replenished to make up for losses.

The following are typical results of two continuous runs with normal butane and isobutylene, showing the effect of varying the molar ratio of normal butane to isobutylene from 5:1 to 10:1.

Table V

N-butane/isobutylene		
mol ratio	5	10
Temperature °F.	70	70
Contact time, min.	60	60
Yield stabilized alkylate, weight percent on olefin (aver.)	105	151
Vol. percent 311° F. E. P.	70.4	93.1
Bromine No.	<1	<1
Octane No. C. F. R. M. clear	81.3	80.2
Octane No. C. F. R. M. +3 cc. TEL/gal.		95.0
Yield of isobutane, mol per cent on olefin, aver.	37.2	190
Pounds of alkylate per pound of catalyst, approx.	2.5	>1
Pounds of isobutane per pound of catalyst, approx.	1.4	>5

The above runs were carried out with continuous recirculation of catalyst to obtain a measure of catalyst life. During the course of the runs, it was noticed that the catalyst tends to form a small amount of hydrocarbon complex; but this is quite small in comparison to the amount formed with aluminum chloride, for example. The efficiency of the catalyst was eventually lowered; and when the yield of alkylate and/or isobutane has dropped to a predetermined point, as determined by direct measurement or by extrapolation of the curve for the run, the latter was terminated. It will be noted from the above that a 10:1 molar ratio of normal butane to isobutylene is superior to a lower molar ratio from the standpoint of yield of total stabilized alkylate, volume percent of 311° F. end point fraction in the alkylate, yield of isobutane and catalyst life. It will be noted from Table V supra, that the alkylate produced from n-butane in accordance with this invention has a high lead susceptibility, since the addition of 3 cc. of tetraethyl lead per gallon of alkylate raised the C. F. R. M. octane from 80 to 95.

The following data are from representative continuous runs carried out in the same manner as described above, and show the effectiveness of the olefins, ethylene, propylene and isobutylene, in this process:

30

Table VI

Olefin used	Ethylene	Propylene	Isobutylene
35 n-butane/olefin mol ratio	10/1	10/1	10/1
Reaction temp., °F.	70	70	70

Mol percent basis olefin	300	250	190
Mol percent basis n-butane	30	25	19
Pounds alkylate per pound catalyst charged	>5.5	>5.3	>4.0
Pounds isobutane per pound catalyst charged	>12.0	>8.3	>10.0

Contrary to previous experience in the alkylation of an isoparaffin with an olefin in the presence of conventional catalysts such as H_2SO_4 and HF wherein the C_4 olefins have been found superior and ethylene reacts only with difficulty if at all, the effectiveness of the olefins in the present process of alkylating normal paraffins is found to vary inversely with the molecular weight of the olefin. Thus, ethylene has been found to give the best results followed by propylene and isobutylene in that order.

In continuous operation, a portion of the catalyst may be continuously withdrawn from the system and the remaining catalyst fortified by the addition of either HF or BF_3 or both, such as by being introduced with the hydrocarbon charge. It will be also understood that the reaction products can be fractionated to separate any unreacted normal paraffin and the latter recycled to the system to increase the yield on the basis of the normal paraffin charge.

It has been further found that the presence of a small amount of iron, such as in the form of the metal or metal alloy, has a distinct promoting effect upon the reaction. To illustrate this effect, continuous runs were carried out in a steel reactor in one case and in a copper-lined reactor free from exposed iron or steel surfaces in the other case. The following are data and results

of these runs employing normal butane with propylene:

Table VII

Reactor	Steel	Copper Lined
Olefin used	Propylene	Propylene
n-Butene/Olefin Mol Ratio	10/1	10/1
Temp., °F.	70	70
Contact Time, Minutes	60	60
Yield, debutanized alkylate, Wt. percent on olefin	157	78
Pounds alkylate per pound catalyst	>7.0	1.8
Yield Isobutane, Wt. per cent on olefin	256	169
Yield Isobutane, Wt. percent on n-butane	18.3	12.3
Pounds Isobutane per pound catalyst	>10.3	4.0

It is also contemplated that salts or compounds of iron, such as ferric and ferrous fluorides, iron salts of boric and fluoroboric acids, etc., may be employed for this purpose. Likewise, it is contemplated that other metals above hydrogen in the electrochemical series, such as cobalt, nickel, manganese, etc., as well as alloys and compounds thereof may be used for this promotional effect.

In either batch or continuous operation, the promotional effect may be obtained by immersing a strip of cold rolled steel or other promoter metal in the reactor, which latter together with the impeller and shaft are preferably constructed of a suitable resistant metal or lining, such as with a copper lining or of stainless steel or Monel metal, to resist corrosion. The reactor may be fitted with a readily replaceable plug or pipe of the promoter metal, so that this is maintained in fixed position within the reactor and does not interfere with the rotation of the impeller and agitation of the contents of the reactor. It is thought that the promoter metal may function as a suppressor of complex formation, giving longer catalyst life. For purposes of easy description, it will be understood that the expression "metal promoter" as used in the specification and claims signifies any of the above mentioned metals, alloys or metal compounds having this promotional effect.

From the above description, it will be apparent that the present invention provides a method of alkylating a normal paraffin with an olefin with concomitant isomerization or production of isobutane, wherein a yield of alkylate of at least about 75-90% of the theoretical on the basis of the olefin charged, and an accompanying yield of isobutane amounting to at least about 20-30% on the basis of the normal paraffin charged, are obtained. The alkylate consists largely of isopentane and hexanes regardless of the olefinic component of the charge, boils almost entirely below 300° F., is substantially completely saturated, has high lead susceptibility, and is an excellent blending stock from the standpoint of volatility and octane blending value, particularly for leaded fuels. The present invention is thought particularly valuable in providing a means for utilizing available refinery supplies of normal butane, ethylene, and propylene, thus providing a one-step process for simultaneously effecting alkylation with the production of alkylate blending stock, and the concomitant production of substantial quantities of isobutane for use in conventional isoparaffin-olefin alkylation processes.

While the invention has been described above in connection with the use of an olefin for reacting with the normal paraffin, it is to be understood that other alkylating agents which function similarly to olefins in the alkylation reaction can be employed. For example, alkyl esters, such

as alkyl fluorides, may be used. These alkyl esters may be produced by absorbing an olefin in a suitable mineral acid, which may be the same as the catalyst employed in the subsequent alkylation step. The acid solution of the olefin absorption product may be passed directly to the alkylation zone; or the alkyl ester may be separated from the absorption acid by the use of a suitable solvent, such as normal butane or other normal paraffin, and the purified ester then transferred to the alkylation reaction zone. Also, various aliphatic alcohols and ethers, such as tertiary or secondary butyl alcohol, isopropyl alcohol, butyl ether, etc., may be used as the alkylating agent, although the latter are not generally preferred for the present process since water is liberated in the reaction requiring frequent replacement of catalyst.

Obviously many modifications and variations of the invention, as hereinbefore set forth, may be made without departing from the spirit and scope thereof, and therefore only such limitations should be imposed as are indicated in the appended claims.

I claim:

1. The method of treating a normally liquid paraffinic naphtha fraction to improve the volatility and other properties thereof and to concomitantly produce isobutane, which comprises 20 contacting the naphtha in liquid phase in the presence of a minor but effective amount of an added olefin at ordinary temperatures below about 150° F. with a mixed catalyst consisting essentially of a major proportion by weight of substantially anhydrous liquid HF and a minor but effective proportion by weight of BF_3 of the order of about 4-20 mol per cent on the basis of the mixed catalyst, and separately recovering the resultant normally liquid hydrocarbons and the produced 30 isobutane from the reaction products.

2. The method which comprises introducing a normal paraffin hydrocarbon essentially free from isobutane and an aliphatic alkylating agent selected from the group consisting of olefins,

45 alkyl esters, alcohols and ethers, with the normal paraffin in substantial molar excess of the alkylating agent, into a reaction zone, and reacting the mixture therein in the substantial absence of added isobutane and in the presence

50 of a mixed catalyst consisting essentially of a major proportion by weight of substantially anhydrous liquid HF and a minor but effective proportion of the order of 2-20 mol percent of BF_3 on the basis of the mixed catalyst under conditions including a temperature of about 0-150° F.

55 and sufficient pressure to maintain at least the normal paraffin in liquid phase, such that normal paraffin is alkylated by the aliphatic alkylating agent to produce substantially saturated motor fuel hydrocarbons with the concomitant production of a substantial amount of isobutane, and

60 separately recovering the motor fuel hydrocarbons and the isobutane from the reaction products.

65 3. The method according to claim 2, wherein the normal paraffin is normal butane, and the aliphatic alkylating agent is a normally gaseous olefin.

4. The method of manufacturing substantially 70 saturated hydrocarbons boiling within the gasoline range which comprises introducing essentially a low boiling normal paraffin and an olefin, with the normal paraffin in substantial molar excess of the olefin, into a reaction zone, and reacting 75 the mixture therein in the substantial absence

11

of added isobutane and in the presence of a mixed catalyst consisting essentially of a major proportion by weight of substantially anhydrous liquid HF and a minor but effective proportion of about 4-20 mol per cent of BF_3 on the basis of the mixed catalyst under conditions including a temperature of about 0-150° F. and sufficient pressure to maintain at least the normal paraffin in liquid phase, such that normal paraffin is alkylated by the olefin to produce substantially saturated normally liquid hydrocarbons within the gasoline boiling range, separately recovering from the reaction products said produced normally liquid hydrocarbons and unconverted normal paraffin substantially free from isoparaffin of corresponding molecular weight, and recycling recovered unconverted normal paraffin substantially free from isoparaffin of corresponding molecular weight to said reaction zone.

5. The method according to claim 4, wherein the normal paraffin is normal butane, and the olefin is a normally gaseous olefin.

6. The method of producing isobutane which comprises introducing a normal paraffin essentially free from isobutane together with a minor but effective amount of an olefin, providing a molar ratio of normal paraffin to olefin in excess of 10:1, into a reaction zone, and reacting the same therein in the presence of a mixed catalyst consisting essentially of a major proportion by weight of substantially anhydrous liquid HF and a minor but effective proportion of the order of about 6-20 mol per cent of BF_3 on the basis of the mixed catalyst under conditions including a temperature of about 70-150° F. and sufficient pressure to maintain at least the normal paraffin in liquid phase, such that a substantial amount of isobutane is produced in the resulting reaction, and recovering the isobutane from the reaction products.

7. The method according to claim 6, wherein the normal paraffin is normal butane, and the olefin is a normally gaseous olefin.

8. The method of isomerizing a normal paraffin hydrocarbon which comprises introducing a normal paraffin hydrocarbon substantially free from isoparaffin of corresponding molecular weight and a small but effective amount of an olefin, providing a normal paraffin to olefin molar ratio in excess of about 10:1, and reacting the mixture therein in the presence of a mixed catalyst consisting essentially of a major proportion by weight of substantially anhydrous liquid HF and a minor but effective proportion of the order of 6-20 mol per cent of BF_3 on the basis of the mixed catalyst under conditions including a temperature of about 70-150° F. and sufficient pressure to maintain at least the normal paraffin in liquid phase, such that a substantial amount of isoparaffin of corresponding molecular weight is

12

produced in the reaction, and recovering said isoparaffin from the reaction products.

9. A method of making substantially saturated branched-chain hydrocarbons which comprises charging a normal paraffin hydrocarbon to a reaction zone, adding a minor mol proportion, based on the normal paraffin, of an olefin hydrocarbon to the reaction zone, reacting the hydrocarbons in the presence of a catalyst comprising essentially substantially anhydrous HF and a minor mol proportion based on the total catalyst, of BF_3 , under reaction conditions wherein the pressure is such as to maintain the hydrocarbons and the HF in liquid phase, wherein the temperature is substantially room temperature and wherein sufficient time is given for the reaction to form substantially saturated branched-chain hydrocarbons.

10. A method of making substantially saturated branched-chain hydrocarbons which comprises charging a normal paraffin hydrocarbon to a reaction zone, adding a minor mol proportion, based on the normal paraffin, of an olefin hydrocarbon to the reaction zone, reacting the hydrocarbons in the presence of a catalyst comprising essentially substantially anhydrous HF and a minor mol proportion based on the total catalyst, of BF_3 , under reaction conditions wherein the pressure is such as to maintain the hydrocarbons and the HF in liquid phase, wherein the temperature is within the range of about 50° F. to about 150° F. and wherein sufficient time is given for the reaction to form substantially saturated branched-chain hydrocarbons.
